FUEL INJECTION METERING CONTROL MECHANISM

Lawrence C. Dermond, Rochester, N.Y., assignor to General Motors Corporation, Detroit, Mich., a corporation of Delaware

Filed Mar. 24, 1958, Ser. No. 723,194

5 Claims. (Cl. 261—69)

The present invention relates to a fuel injection system of the mass air flow type utilizing a metering control valve disposed in a fuel chamber and which valve is controlled by a diaphragm device responsive to mass air flow.

More specifically the present invention relates to a simplified linkage arrangement through which the fuel metering valve is controlled. As described in copending application Serial No. 591,889, Dolza, filed June 18, 1956, the metering valve linkage mechanism is basically controlled by a mass air flow responsive diaphragm device the operation of which is modified by a power enrichment device. The latter device is adapted to provide an economical fuel flow range for normal light load engine operation at the same time insuring increased fuel flow under high power demand situations. The earlier means for achieving this fuel flow rate variability in the metering valve linkage was by means of providing a shiftable fulcrum controlled by a manifold vacuum actuated servo. Thus by shifting the fulcrum the mechanism advantage of the linkage system was varied to relatively increase or decrease the fuel flow rate.

This earlier means for making the linkage operation responsive to engine load while operative has been modified in accordance with the present teaching to better facilitate control by the relatively low vacuum control forces available to actuate the meter valve diaphragm. Since such mass air flow generated vacuum control force is relatively low, particularly under low air flow conditions, any hysteresis in the linkage system due to friction, looseness, etc. tends to modify or delay the control of the metering valve. The present invention is directed toward reducing such hysteresis and simplifying such linkage system particularly in relation to its coaction with the power enrichment device.

In the present invention engine load modifications of fuel flow rates are achieved by a greatly simplified lever system for varying mechanical advantages. The lever system also includes a spring the rate of which is uniquely varied to further facilitate changes in engine load varied fuel rates.

Further objects and advantages of the present invention will be apparent from a perusal of the detailed description which follows.

In the drawings:

Figure 1 is a diagrammatic representation of a fuel injection system embodying the present invention; and

Figure 2 is an enlarged perspective view of the improved metering valve linkage system.

The fuel injection system in general comprises an air take passage 10 having a throttle valve 12, a plenum chamber 14 supplied by the air intake and a plurality of in-

dividual intake passages 15 leading from the plenum chamber and respectively communicating with each of the cylinders of the engine. A fuel metering device is shown generally at 16 and includes a fuel chamber 18 having an inlet 20 the flow through which is controlled by a conventional float controlled fuel inlet valve 22. A pump 24 is submerged in the fuel chamber and is adapted to pressurize the fuel and supply the same through a conduit 26 to a metering valve 28. A plurality of fuel conduits 30 communicate supply conduit 26 with individual fuel nozzles 32 disposed in the intake passages 15 proximate the engine cylinders.

Metering valve 28 includes a ball element 34 disposed within a recess 36 and which element is adapted to be moved upwardly by the fluid under pressure in conduit 26 whereby a portion of the supplied fuel will be bypassed through radial passages 38 back to the fuel chamber. Opposing the fuel pressure opening movement of the valve element 34 is a control rod 40 centrally fixed at its other end to a diaphragm 42 mounted in the cover wall 44 of the fuel chamber 18 and peripherally clamped to said cover wall by a cover 46. The diaphragm control rod 40 is operatively connected to the valve element 34 through an intermediate lever 48 which is part of a power enrichment mechanism 50 to be subsequently described. The upper diaphragm chamber 52 is atmospherically vented through a conduit 54 while the lower diaphragm chamber 56 is communicated by a conduit 58 with an annular vacuum chamber 60 formed in the venturi portion 62 of the air intake passage 10. As the mass or quantity of air flow increases through intake passage 10 with an opening of throttle valve 12, the vacuum force in chamber 60 and conduit 58 will be increased causing the diaphragm 42 to be moved downwardly to oppose the fuel pressure-opening of the valve element 34 and to reduce the fuel being bypassed back to chamber 18. The result of the increase in mass air flow is therefore a corresponding increase in the quantity of fuel supplied to the nozzles 32.

The power enrichment mechanism 50 is provided in order to insure maximum fuel economy under normal operating conditions and increased fuel flow under conditions of high power demand. This mechanism includes a servo piston 64 slidably mounted in a casing 66 and defining therewith a chamber 68 connected through a conduit 70 with manifold or plenum 14. A spring 72 normally urges the piston 64 in an upwardly direction. A bell crank lever 74 is pivotally mounted at 76 and includes an arm 78 articulated to piston 64 by a link 80. The other arm 82 of bell crank lever 74 is articulated to lever 48 which, as already noted, operatively interconnects diaphragm control rod 40 and the valve element 34.

Lever 48 and bell crank arm 82 are pivotally connected by a pin 88. A spring 90 is looped about pin 88 and includes a first leg 92 biasing against arm 82 and a second leg 94 biasing against the underside of lever 48. Spring 90 rotatably biases lever 48 in a clockwise direction relative to arm 82. This action is then in opposition to the vacuum force in diaphragm chamber 56, the latter tending to maintain valve element 34 in a seated position. The counter-clockwise force of spring 90 is such that under normal operating conditions, i.e. pin 88 in rightmost position, it will counteract the weight of diaphragm control rod 40 and lever 48. Since the vacuum control forces acting on diaphragm 42 are relatively small it is necessary to compensate for the weights of elements acting thereon lest

they upset the control of metering valve 34. Unless compensated by spring 90, the weight of rod 40 and lever 48 would urge valve 34 in a direction reducing the fuel bypassed and thereby increasing the fuel supplied to the nozzles.

A pair of spaced stops 84 and 86 are provided against which the free end of lever arm 78 is adapted to abut in accordance with the position of piston 64. Under normal operating conditions the manifold vacuum in chamber 68 is sufficiently high to overcome the spring 72 to move the piston downwardly causing the lever arm 78 to abut against the lower or economy operation stop 84. This movement of lever 74 causes the pivot point 88 between lever 48 and arm 82 to move to the right increasing the torsion on spring 90 and causing the latter to fully offset the weight of lever 48 and rod 40, supra. The rightward movement of pin 88 also shifts the fulcrum point of the lever system such that the mechanical advantage of the vacuum force acting downwardly on rod 40 is relatively decreased with respect to that of the fuel pressure urging valve 34 upwardly. The result of increased torsion on spring 90 and increased resultant effect of fuel pressure on lever 48 is to cause valve 34 to bypass more fuel thereby leaning out the fuel-air mixture for more economical engine operation.

On the other hand, under conditions of high power demand, such as occur with a sudden depression of the accelerator pedal, the manifold vacuum in chamber 68 is reduced sufficiently to permit the spring 72 to raise piston 64 until lever arm 78 abuts the upper or power stop 86 shifting the pivot or fulcrum point 88 to the left. This action decreases the torsion on spring 90 and adds the weight of rod 40 and lever 48 to the vacuum force tending to close valve element 34. Likewise the vacuum force acting through rod 40 is relatively increased with respect to the fuel force acting on valve 34, again due to changes in mechanical advantages, whereby fuel flow to nozzles 32 is increased. It is apparent that this latter operation provides fuel enrichment and hence additional power until such time as the load on the engine is suitably decreased.

A novel idle fuel flow control device is shown with the illustrated fuel injection system and forms the basis of copending application of Dermond S.N. 723,196 filed March 10, 1958. The idle fuel control device will now be described briefly.

A boss 93 is formed on the fuel chamber cover 44 and is adapted to be communicated with a suitable conduit connected with a source of manifold vacuum. As set forth in copending application Serial No. 648,100 Dermond et al., filed March 25, 1957, now Patent No. 2,898,096 granted August 4, 1959, it is desirable to eliminate the fuel vapors which tend to collect above the fuel level in chamber 18 as is particularly likely to happen under hot operating conditions. Unless eliminated such vapors interfere with the normal control of metering valve 28 by diaphragm 42. These vapors may be eliminated from the fuel chamber by maintaining a slight depression above the fuel level whereby the vapors are drawn into the manifold. The manifold vacuum in fuel chamber 18 is reduced to any desired value by any suitable orifice 95 which may be disposed in boss 93.

It is apparent that with the fuel chamber maintained under a slight manifold depression, and for the moment ignoring the metering control force transmitted by diaphragm control rod 40, a pressure differential or drop will exist across the metering control valve element 34 due to the pressure of the fuel acting on one side thereof and the aforesaid manifold vacuum on the other side thereof. This pressure differential across the valve element 34 will therefore determine the rate of fuel flow through the metering valve to the nozzles 32 with other control forces remaining substantially constant as would be the case during idling operation. By varying this pressure differential across element 34, it is possible

therefore to vary the rate of fuel flow through the metering valve.

Thus, to control idle fuel flow an adjustable valve element 96 is provided in boss 93 and includes a tapered end portion 98 adapted to cooperate with an atmospheric vent port 100. The vacuum level in the fuel chamber 18 may thus be varied in accordance with the degree of opening of said atmospheric port. With the valve 96 completely blocking the atmospheric bleed port 100, a maximum vacuum force will act within the fuel chamber causing a corresponding maximum pressure drop across valve element 34. As the atmospheric vent port 100 is progressively opened by valve 98, the pressure within the fuel chamber approaches atmospheric reducing the pressure drop across valve element 34 and thereby increasing the fuel flow to the nozzles under idling conditions.

In this way a simple device is provided for controlling idle fuel flow by utilizing a control force otherwise available in the system. It is apparent that various structural modifications may be made in the subject invention within the scope of the hereinafter appended claims.

I claim:

1. A charge forming device for an internal combustion engine comprising a source of fuel under pressure, a valve device for supplying metered quantities of fuel to the engine, said valve device including a movable valve element, said fuel under pressure acting on the element to decrease fuel flow, and means for controlling the actuation of said valve element, said means including a lever operatively connected to said element, an engine demand responsive device operatively connected to said lever and adapted to move said element to increase fuel flow as said demand increases, means biasing said lever in a direction decreasing fuel flow through the valve device, and an engine load responsive device for modifying the operation of said biasing means to increase fuel flow under high load conditions and to decrease fuel flow under low load conditions.

2. A charge forming device for an internal combustion engine comprising a source of fuel under pressure, a valve device for supplying metered quantities of fuel to the engine, said valve device including a movable valve element, said fuel under pressure acting on the element to decrease fuel flow, and means for controlling the actuation of said valve element, said means including a first lever operatively connected to said element, an engine demand responsive device operatively connected to said lever and adapted to move said element to increase fuel flow as said demand increases, a bifurcated lever having one leg articulated to said first lever, said bifurcated lever mounted upon a fixed pivot, a torsion spring operatively connected between said first lever and said one leg of the bifurcated lever and urging said first lever in a fuel flow decreasing direction, and an engine load responsive device articulated to the other leg of said bifurcated lever, said device being adapted to rotate the bifurcated lever to vary the rate of said torsion spring to vary the rate of fuel flow through said valve device.

3. A charge forming device for an internal combustion engine comprising a source of fuel under pressure, a valve device for supplying metered quantities of fuel to the engine, said valve device including a movable valve element, said fuel under pressure acting on the element to decrease fuel flow, and means for controlling the actuation of said valve element, said means including a lever operatively connected to said element, an engine demand responsive device operatively connected to said lever and adapted to move said element to increase fuel flow as said demand increases, a torsion spring biasing said lever in a direction decreasing fuel flow through the valve device, and an engine load responsive device adapted to vary the rate of said spring to increase fuel flow under high load conditions and to decrease fuel flow under low load conditions.

4. A charge forming device as set forth in claim 2 in

which the engine load responsive device includes a pair of spaced stops, a servo piston articulated to the other leg of said bifurcated lever, a spring member biasing said piston to abut said other leg against one of said stops to decrease the rate of the torsion spring, and means communicating manifold vacuum with said piston whereby under normal load conditions said vacuum will overcome the force of the spring member to move said other leg against the other of said stops to increase the rate of the torsion spring.

5. A charge forming device as set forth in claim 2 in

which said bifurcated lever is articulated to said first lever through a pin connection, said torsion spring being concentrically mounted on said pin and terminating in a pair of legs respectively biasing against said first lever and said one leg of the bifurcated lever.
